UNITED STATES PATENT OFFICE.

ERNESTO FUCHS, OF TRENTON, NEW JERSEY.

DESIGN FOR A POWDER BOX OR CAN.

46,334.

Specification for Design.

Patented Sept. 1, 1914.

Application filed June 21, 1912. Serial No. 705,129. Term of patent 3½ years.

To all whom it may concern:

Be it known that I, ERNESTO FUCHS, a citizen of the United States, residing at Trenton, in the county of Mercer and State of New Jersey, have invented a new, original, and ornamental Design for a Powder-Box or Can, of which the following is a specification, reference being had to the accompanying drawings, forming a part thereof, and in which the figure is a perspective

view of a powder box or can, showing my new design.

I claim:

The ornamental design for a powder box or can, as shown.

ERNESTO FUCHS.
